LAMP-ROTATING CLAMP FOR ATTACHMENT
TO TUBULAR LAMPSRobert T. Riker and Joseph H. Molat,
New York, N. Y.

Application December 14, 1945, Serial No. 635,128

8 Claims. (Cl. 240—51.11)

(Granted under the act of March 3, 1883, as
amended April 30, 1928; 370 O. G. 757)

1

This invention relates in general to a clamp for use in rotating tubular fittings, and in particular to such a device for use in connection with fluorescent light fixtures located in elevated positions or in other positions that are inaccessible to hand operation.

Fluorescent lamps now in commercial use are provided with a pair of spaced contact pins at each end for insertion in sockets constructed and arranged to accommodate the pins and support the lamps. The contact pins are disposed in a common plane and the usual type socket is provided with a slot into which the pins are inserted by moving the lamp transverse to its longitudinal axis. The lamp is then rotated 90° about said axis releasably to lock the lamp in its sockets. Since the fluorescent light fixtures are often located in elevated positions or in other positions inaccessible to the hand, a lamp changer, such as that described in my copending application, Serial No. 635,130, filed December 14, 1945, is often used to eliminate the necessity of step-ladders, staging or scaffolds. While in some instances lamp changers are provided with means for both grasping and rotating the fluorescent lamp or tube such devices are often too bulky to be inserted in the limited space provided in some fixtures. It is often desirable, therefore, to use a gripping device, such as that described in my above-identified copending application, which can be inserted into a fixture having limited space and to use some auxiliary means then to rotate the fluorescent tube.

It is an object of this invention, therefore, to provide such a tube twisting or rotating device.

It is a further object to provide a device that enables the tube to be rotated only through such an angle as is necessary properly to align the contact pins of a fluorescent tube so that the tube can be removed.

Further objects and advantages of this invention, as well as its construction, arrangement and operation, are apparent from the following description and claims in connection with the accompanying drawing, in which:

Fig. 1 is an end view showing of the clamp embodying this invention upon a fluorescent tube.

Fig. 2 is a fragmentary side elevation looking from the left of Fig. 1, and

Fig. 3 is a sectional view of a fluorescent lamp fixture showing the position of the clamp of this invention upon the fluorescent tube thereof when the tube is properly positioned in its socket.

The tube rotating device of this invention com-

prises a ring-shaped clamp 10, of suitable resilient material adapted to be clipped or inserted upon a tube 11 in approximately the position shown in Fig. 2, and secured thereon by any suitable means such as a bolt 12 and nut 14 through a hole in projecting ears 16. The clamp 10 is further provided with hook-shaped projections 18 and 19 spaced on the periphery thereof approximately one quarter and one half way respectively around the clamp from the projecting ears 16. Substantially midway around the periphery of the clamp 10 between the projecting ears 16 and hook 19 is a projecting member 20, referred to hereinafter as a limit stop. The limit stop 20 and nearest projecting ear 16 are slightly greater than 90° apart for a reason that is apparent from the description of the operation following.

Figs. 1 and 2 show the clamp 10 in position upon a fluorescent tube 11 having the conventional contact pins 24. The clamp 10 is so placed upon the tube that a plane through the longitudinal axis of the tube and through projecting ears 16 and the opposing projecting element hook 19 is just out of vertical alignment with the contact pins 24. When the clamp is so placed the projecting elements 18 and 19 are in the position shown in Fig. 3 when the tube is properly assembled in the fixture, that is, element 19 projects substantially horizontally from the clamp 10 while element 18 projects substantially vertically downward.

Fig. 3 shows a fluorescent lamp fixture 26 having a socket attachment 28 secured thereto in the conventional manner by means of a bolt 30 spaced slightly inward from its end. The clamp 10 is placed upon the fluorescent tube 11 so that when the tube 11 is in its proper position in socket 28 either the limit stop 20 or one of the projecting ears 16 contacts the head of the bolt 30. If the lamp fixture does not contain such a bolt, one can be provided or the projecting elements can be made of such dimensions as to engage the base of the fixture itself. It is assumed that the tube 11 and clamp 10 are in assembled position in Fig. 3 with the contact pins 24 horizontally disposed within the socket.

In operation, to remove the tube 11 it is first lightly gripped with the conventional lamp changer (such as described in my copending application referred to above). The tube is rotated by pulling down upon the hook member 19 with any convenient implement, such as a hook upon the end of a long shaft. When the tube is rotated 90°, one of the ears 16 contacts the head of the bolt 30, stopping the tube 11 in the proper

position to enable it to be withdrawn from its sockets.

In replacing the tube the reverse procedure is employed. The tube is inserted with the lamp changer and then rotated by pulling on element 18. When the proper degree of rotation is effected limit stop 20 contacts bolt head 30 and the tube is properly positioned within its sockets.

The device of this invention thus very effectively solves the problem of removing fluorescent tubes from remotely located light fixtures.

It is to be understood that various modifications and changes can be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A lamp-rotating device for attachment to elongated lamps of the type interlocked and released from their fixtures by rotation of the lamp about its longitudinal axis, comprising a ring-shaped clamp adapted to be positioned on said elongated lamp, a pair of projecting lugs upon said clamp, means connecting said lugs for securing said clamp to said lamp, a pair of hooks positioned upon the periphery of said clamp facing in opposite directions whereby said clamp and tube can be rotated in either direction, and a projecting element upon the periphery of the clamp spaced from said hooks and said lugs, said projecting element and said lugs being adapted to cooperate with said fixture to limit the degree of rotation of said clamp and tube to approximately 90 degrees within said fixture and said hooks being spaced relative to said lugs and projecting element to extend substantially horizontally outward and substantially vertically downward respectively from said clamp when said tube and clamp are at one limit of rotation within said fixture.

2. A lamp-rotating device for attachment to an elongated lamp of the type interlocked and released from a fixture by rotation of the lamp about its longitudinal axis, said device comprising a ring-shaped clamp adapted to be positioned on an elongated lamp, a pair of projecting lugs upon said clamp, means connecting said lugs for fixedly securing said clamp to the lamp, a pair of hooks positioned upon the periphery of said clamp facing in opposite directions whereby said clamp and the supporting lamp may be rotated in either direction, and a projecting element upon the periphery of said clamp spaced from said hooks and said lugs, said projecting element and said lugs being adapted to cooperate with the fixture to limit the degree of rotation of said clamp and the supporting lamp to approximately 90 degrees relative to the fixture, and said hooks being spaced relative to said lugs and projecting element to extend substantially horizontally outward and substantially vertically downward respectively from said clamp when said clamp and the supporting lamp are at one limit of rotation relative to the fixture, said lugs and projecting element being on one side of a plane including the lamp axis, said hooks being on the other side of the plane.

3. A device for attachment to a lamp of the type adapted for rotation in a fixture between limits, said device comprising a clamp adapted to be fixedly secured about the periphery of a lamp, means for fixedly securing said clamp to the lamp and

including a portion forming a projection on the periphery of said clamp, a pair of hooks on the periphery of said clamp facing in opposite directions whereby said clamp and the supporting lamp may be rotated in either direction, and a second projection on the periphery of said clamp, said projections being adapted to cooperate with the fixture to limit rotation of said clamp and the lamp, said hooks being arranged to extend one substantially horizontally and the other substantially vertically downward from said clamp when the latter is at a limit of rotation, said projections being on one side of a plane including the lamp axis, said hooks being on the other side of the plane.

4. A device for attachment to a lamp of the type adapted for rotation in a fixture between limits, said device comprising a clamp adapted to be fixedly secured about the periphery of a lamp, means for fixedly securing said clamp to the lamp, a plurality of projections extending outwardly from the periphery of said clamp, said projections being adapted to cooperate with the fixture to limit rotation of said clamp and the lamp, two of said projections being arranged to extend one substantially horizontally and the other substantially vertically downward from said clamp when the latter is at a limit of rotation, said two of said projections being on one side of a plane including the lamp axis, the other two projections being on the other side of the plane.

5. A device for attachment to a lamp of the type adapted for rotation in a fixture between limits, said device comprising a clamp adapted to be fixedly secured about the periphery of a lamp, means for fixedly securing said clamp to the lamp, a plurality of projections extending outwardly from the periphery of said clamp, said projections being adapted to cooperate with the fixture to limit rotation of said clamp and the lamp, two of said projections being exposed and spaced apart an angular distance corresponding to the angle of rotation of said clamp and the lamp between their limits, said two of said projections being on one side of a plane including the lamp axis, the other two projections being on the other side of the plane.

6. A device for attachment to a lamp of the type adapted for rotation in a fixture, said device comprising a clamp adapted to be fixedly secured about the periphery of a lamp, means for fixedly securing said clamp to a lamp, and four projections extending substantially radially outward from the periphery of said clamp, said projections being located on said clamp at approximately 90 degree intervals, two of said projections in adjacent rotation forming hooks each of which has a terminal portion extending in a direction away from the other hook, said two of said projections being on one side of a plane including the lamp axis, the other two projections being on the other side of the plane.

7. A device for attachment to a lamp of the type adapted for rotation in a fixture, said device comprising a clamp adapted to be fixedly secured about the periphery of a lamp, means for fixedly securing said clamp to a lamp and a pair of hooks extending from the periphery of said clamp, said hooks being exposed and spaced apart an angular distance corresponding to the angle of rotation of said clamp and the lamp between their limits, each hook having a stem portion disposed substantially radially with respect to said clamp and an offset terminal portion extending in a direction away from the other hook.

8. A lamp-rotating device for attachment to elongated lamps of the type interlocked and released from their fixtures by rotation of the lamp about its longitudinal axis, comprising a ring-shaped clamp adapted to be positioned on said elongated lamp, a pair of projecting lugs upon said clamp, means connecting said lugs for securing said clamp to said lamp, a pair of hooks positioned upon the periphery of said clamp facing in opposite directions whereby said clamp and tube can be rotated in either direction, and a projecting element upon the periphery of the clamp spaced from said hooks and said lugs, said projecting element and said lugs being adapted to cooperate with said fixture to limit the degree of rotation of said clamp and tube to a predetermined angle within said fixture and said hooks being spaced relative to said lugs and pro-

jecting element to extend substantially horizontally outward and substantially vertically downward respectively from said clamp when said tube and clamp are at one limit of rotation within said fixture.
